UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed December 31, 1919. Serial No. 348,578.

To all whom it may concern:

Be it known that I, CHARLES L. GOODRUM, a citizen of the United States, residing at New York, in the county of New York and State of New York, have invented certain new and useful Improvements in Machine-Switching Telephone-Exchange Systems, of which the following is a full, clear, concise, and exact description.

This invention relates to machine switching telephone exchange systems, and more particularly to such systems wherein toll connections are completed by an operator. Its object is to provide an improved circuit arrangement for checking the number given the operator by the calling subscriber, such toll operator's positions being selected over an automatic switch or switches. In such event she ordinarily has no means of ascertaining the number of the calling line except from the subscriber.

In accordance with this invention, the operator is provided with a special set of automatic switches by means of which she may connect with multiples of the calling line and impress thereon a tone which is transmitted back over the connection built up for the subscriber and into the head-set of such operator, this tone being impressed upon the talking conductors of the special switches and of the switches in the connection built up for the subscriber in multiple, so that while the operator can hear the tone, the calling subscriber cannot. It is desirable to avoid impressing unnecessary tones on subscribers' lines to prevent confusion, since it is becoming the practice to notify subscribers by means of different tones of the condition or progress of calls as, for example, busy and ringing tones.

Referring to the drawing, A designates the calling substation which, by means of a first selector B, is associated with a trunk C which terminates in a jack before the toll operator, who, in response to the lighting of the calling lamp associated therewith, extends the call by means of a plug to a trunk D terminating in a plug, which, after the operator has secured the desired number, she inserts into a jack T which terminates in a first selector. This selec-

tor and succeeding automatic switches are set by the operator to build up a connection to a desired line. The circuits and apparatus are not shown in detail since they may be identical with those shown in Fig. 1, parts 1 and 2 of Patent #1,251,350, December 25, 1917, to Gerald Deakin. The operator then by means of her key DK' connects her dial CD³ to a first selector L and sets the same to pick out a connector M, which she then sets on the line given her by the calling subscriber. Upon completing the connection she depresses her listening key LK, and if the subscriber gave the correct number she will hear a tone in her head-set, from the tone source TT over the talking conductors in multiple. If, however, the calling subscriber gave some other number, wipers 112 and 113 would have been connected to multiples of some line which is not connected back through cord circuit D, so that when the operator connected the tone 118 to the checking circuit, the signal would not be received and she would know that something is wrong. After the checking operation, the operator by actuating key DK' causes the special switches L, M to be restored.

More specifically, when the toll operator answers the call to ascertain the wants of the calling subscriber, she also requests the number of the calling substation, which in the case of toll service is used to make the toll charge, as is well understood. In the drawings is indicated by the diagrammatic circuits A, B, C, D, T a connection established from calling substation A to trunk T. Trunk T terminates in a selector as shown in figure, part 2, of the patent referred to, which is then set to pick out a connector to connect with the called line as fully shown and described in said patent.

Having ascertained the number of the calling telephone line A, which we will assume is No. 345, the operator throws a calling device key DK' to connect a calling device CD³ in circuit with a selector switch L, this connection resulting in the energization of impulse relay IR³ over the metallic circuit including the contacts of said device CD³, and responsive to energization of IR³ its alternate contact 15' is closed, causing the energization of release

- relay RR^3 which is now maintained energized until a release of the switch is desired. The operator then actuates calling device CD^3 to effect three interruptions of the metallic circuit including IR^3 , whereby said relay is operated three times effecting three operations of vertical magnet VM^3 and three vertical steps of the wipers, in a manner well understood. Secondary relay SR^3 is also energized responsive to these three operations to effect the energization of private magnet PV^3 . After the said three operations of IR^3 , relay SR^3 deenergizes, allowing magnet PV^3 to retract its armature and step the side-switch arms into their second position. A vibratory circuit for rotary magnet RM^3 is thereby established, causing it to operate to step wipers 101 to 105 inclusive into engagement with the first set of contacts 106 to 110 inclusive in the selected level, and due to a mechanical connection the first operation of RM^3 moves the armature of magnet PV^3 into its attracted position, whereby if the first set of contacts engaged lead to a busy second selector M , relay PV^3 is maintained energized and the magnet RM^3 continues to step the wipers until an idle set of contacts is reached, whereby the maintaining circuit for PV^3 is interrupted, causing it to de-energize and move the side-switch arms into their third position thus preventing any further operations of RM^3 and extending the metallic circuit including calling device CD^3 over the heavily marked conductors and through the impulse relay IR^4 to battery, causing its energization.
- Closing of alternate contact 111 of relay IR^4 connects ground to the multiple contacts 106 preventing any other switch L from connecting to switch M , this connection also being adapted to maintain relay RR^3 energized. Also upon closing of alternate contact 111, release relay RR^4 is energized.
- The operator now actuates calling device CD^3 to effect four operations of relay IR^4 whereby four impulses are transmitted through SR^4 , VM^4 , and vertical magnet VM^4 is operated four times to cause four vertical steps of wipers 112, 113, while secondary relay SR^4 due to the closing of its alternate contact 114, causes private magnet RV^4 to step side-switch arm 115' into its middle position after the said four operations. The operator again actuates calling device CD^3 , this time effecting five operations of relay IR^4 resulting in five operations of rotary magnet RM^4 and stepping wipers 112, 113 into engagement with the fifth set of contacts 4, 5, which are the terminals of substation No. 345. During this rotary operation of the wipers, they are disconnected at normal contacts 115, 116 respectively so that no existing connections will be interfered with. After the last said five opera-

tions, private magnet RV^4 steps the side-switch arm into its third position due to the circuit through alternate contact 114.

Thus, it will be seen that if the calling subscriber has given the correct number, a circuit will be established from key DK' over the heavily marked conductors to the terminals of the calling line and then over circuits B , C , D , to operator's circuit O , so that upon the operator throwing her key DK' to connect test-tone device TT in circuit, a signal will be transmitted over the circuit including switches L , M , B and circuits B , C , D , to the operator's telephone set O , which is adapted to be connected to the circuit D by a listening key LK whereby she receives the signal and is thus informed that the subscriber has given the correct number.

This tone circuit may be traced from ground through the secondary of induction coil 118 of the apparatus TT , through the heavily marked conductors in parallel, condensers 119, 120, wipers 102, 105, wipers 112, 113, talking conductors of selector B in parallel, talking trunks C , D in parallel, through the contacts of listening key LK to the opposite ends of the primary winding P , through said primary winding to the ground connection at the middle point of said primary winding. This current is transferred by induction to the secondary winding S from the primary winding P and is heard by the operator by means of her receiver R , the key shown in the head set circuit O being thrown to its alternate position. In its normal position this key disconnects said secondary winding S from said receiver R and connects the receiver to the alternate contacts of the listening key LK so that the operator may communicate with subscribers by a circuit including the trunk conductors in series. An examination of the tone circuit traced will show that the tone current can only pass from ground through the secondary of induction coil 118 of apparatus TT , over the conductors of trunks L , M and multiple wiring between switches M and B in parallel, through the trunk conductors B , C and D in parallel, key LK , the primary winding P of the induction coil in the head set, which primary winding induces current in the secondary winding S , to which the operator's receiver R is connected when the key in the head set is thrown to its alternate position, as described. Since there is no ground at substation A , this tone current cannot flow out over the conductors leading to substation A but must flow over the path just traced, to ground at the middle point of primary winding P of the induction coil in the operator's head set. Therefore, since this current cannot find a path to ground at the substation A , tone will not be heard in the 120

receiver at said substation and the calling subscriber will not be aware of the checking operation being performed by the operator to see whether the subscriber has given the right number.

It will be apparent that if the calling subscriber gave some other number than his own, that wipers 112, 113 would have been connected to terminals 4, 5 of some line 10 which is not connected back through cord circuit D, so that when the operator connected the test tone TT to the checking circuit the signal would not be received and she would know that something was wrong.

15 After the checking operation has been performed, by restoring key DK' to its normal position, the circuit for relay IR⁴ is interrupted causing its restoration, and due to the interruption of its alternate contact 111 20 release relays RR³ and RR⁴ are restored, the restoration of relay RR³ closing its normal contact 16' whereby a circuit for release magnet REM³ is established from ground through normal contacts 15', 16', the winding of REM³ through off-normal switch ON³ to battery, causing the energization of 25 the release magnet, whereby switch L is restored in a well known manner.

Upon restoration of RR⁴, its normal contact 111' is closed whereby an energizing circuit for release magnet REM⁴ is established through off-normal switch ON⁴ causing restoration of switch M in a well-known manner, whereby switches L and M are now 35 available for use in performing other checking operations.

What is claimed is:

1. A telephone system comprising telephone lines, operator controlled link circuits, automatic switches for interchangeably connecting said lines and link circuits responsive to calls over said lines, connection terminals for said lines, operator controlled automatic switches for connecting to 40 said terminals of a calling line, and means including a circuit comprising the talking conductors in parallel for transmitting a characteristic signal to a connected operator's link circuit.

50 2. A telephone system comprising telephone lines, operator controlled link circuits, an automatic switch connected with one of said link circuits responsive to a call over said lines, connection terminals for 55 said lines, operator controlled automatic switches for connecting to said terminals of a calling line, and means for transmitting a characteristic signal over the established talking circuit in parallel including said automatic switches in the operator's link circuit.

60 3. A telephone system including a telephone line, operator controlled link circuits, an automatic switch for connecting said line with one of said link circuits responsive to

a call over said line, means for establishing a circuit over said line, a link circuit whereby the operator may learn the number of the calling telephone line from the calling subscriber, and means controlled by the 70 operator including a circuit over the talking conductors in parallel for ascertaining whether the telephone number given by a calling subscriber is the number of the calling line. 75

4. A telephone system including telephone lines, operator controlled link circuits, automatic switches for interchangeably connecting said lines and link circuits responsive to calls over said lines, means controlled by the operator for establishing a conversational circuit over such a connection whereby she may learn the number of the calling telephone line from the calling subscriber, and means including a circuit over said 80 talking conductors in parallel controlled by the operator for ascertaining whether the telephone number given by the calling subscriber is the number of the calling line. 85

5. A telephone system including a telephone line, operator controlled link circuits, an automatic switch for connecting said line to one of said link circuits responsive to a call over said line, means for establishing a conversational circuit between said calling line and link circuit whereby the operator may learn the number of the calling line from the calling subscriber, operator controlled automatic switches for connecting to the telephone line corresponding to 90 the number given by the calling subscriber, and a circuit including the talking conductors in parallel for determining whether the telephone line connected with is the calling telephone line. 95

100 6. A telephone system including a telephone line, operator controlled link circuits, an automatic switch for connecting said line with an idle one of said link circuits responsive to a call over said line, 105 means controlled by the operator for connecting to the line corresponding to the number given by the calling subscriber, and means including a circuit over said talking conductors in parallel for determining whether the telephone line connected with is the calling telephone line. 110

7. A telephone system comprising calling and called telephone lines, and means controlled by an operator including operator controlled automatic switches and a circuit in parallel over the talking conductors of said switches for checking the number of the calling line. 120

8. A telephone system comprising telephone lines, operator controlled link circuits, switches for interchangeably connecting said lines and link circuits responsive to calls over said lines, connection terminals for said lines, and operator controlled elec- 125

- 5 tromagnetic switches for operatively connecting to the terminals of a line that is calling and is connected to one of said link circuits, and means including a circuit over 60
- 5 the talking conductors in parallel for giving a characteristic signal to the operator. 65
9. A telephone system comprising telephone lines, a central office operator's switchboard, operator controlled link circuits 70
- 10 thereat, switches responsive to calls over said lines for interchangeably connecting said lines and link circuits, called line connection terminals of said lines, and electromagnetic switches controlled by an operator 75
- 15 at the central office switchboard for connecting to the called line terminals of a line that is calling and is operatively connected in telephonic circuit with one of said link circuits, and a circuit including the 80
- 20 talking conductors in parallel for transmitting a tone to the operator. 85
10. A telephone system comprising telephone lines, a called line, connection terminals for said lines, a central office operator's switchboard, operator controlled link circuits 90
- 25 thereat, switches responsive to calls over said lines for interchangeably connecting said lines and link circuits, electromagnetic switches controlled by an operator at 95
- 30 the central office switchboard for connecting to the called line terminals of the calling line, and a circuit including the talking conductors in parallel for transmitting a characteristic signal through the last said 100
- 35 switches through the last terminals and through the first said switches to the operator's link circuit. 105
11. A telephone system including a telephone line, a central office operator's switchboard, an operator's link circuit, means for connecting said telephone line to said link circuit, an operator controlled electromagnetic switch for connecting to said link circuit through terminals of said line, and means including the talking conductors in parallel 110
- 40 for transmitting a tone over said switch to the operator's set associated with said link circuit. 115
12. A telephone system including a telephone line, a central office switchboard, a link circuit at said switchboard, electromagnetically controlled means for connecting said line to said link circuit, a tone source, an operator controlled electromagnetic 120
- 45 means for connecting to said line, a tone from said source in parallel over the talking conductors of said line circuit. 125
- 50 13. A machine switching telephone exchange system including a calling line, a link 130
- 55 circuit, automatic switches adapted upon the initiation of a call to connect said line with an idle link circuit, means controlled by the operator for extending the calling line to the called line, a special circuit controlled by the operator and having associated therewith a tone source, means for connecting said source in parallel to the conductors of said special circuit and thereby to multiples of the calling line and to the link circuit connected to the calling line and over which the connection is built up, an operator's telephone, and a key for connecting the same to said link circuit. 140
14. In a telephone system, a calling line, link circuits, means for automatically connecting a calling line to an idle link circuit, means for extending said link circuit to the called line, a special circuit, a tone source including a primary and secondary winding adapted to be connected thereto and having 80
- its secondary winding grounded at its middle point, means for connecting said special circuit to the calling line terminals, and an operator's circuit associated with said link circuit and including an induction coil having 85
- its primary winding grounded at its middle point, and means for connecting the opposite ends of said primary winding of said link circuit. 90
15. In a machine switching telephone exchange system, a calling line, a first selector, toll trunks, trunk circuits terminating in an operator's position, means under the control of the calling subscriber for causing said selector to seize one of said toll trunks, 95
- means controlled by the operator for extending said trunk into connection with a called line, a checking circuit including automatic switches and a tone source including a primary and secondary winding the secondary 100
- winding of which has its middle point connected to ground, means controlled by the operator for building up a connection over said switches to the calling line and a key for connecting the opposite ends of said secondary winding to the talking conductors of the connection thus built up whereby said tone is transmitted to the talking conductors of the trunk circuit in parallel, an operator's circuit including an induction coil having 105
- the middle point of its primary winding connected to ground, and a key for connecting the opposite ends of said winding to said talking conductors. 110
- In witness whereof, I hereunto subscribe my name this 30th day of December, A. D. 1919.

CHARLES L. GOODRUM.
